PRINTING TAPE REGISTER CABINET OR SIMILAR ARTICLE

Albert Hohmann, Brooklyn, N. Y., assignor to Benjamin Cooper, Brooklyn, N. Y.

Application April 13, 1955, Serial No. 35,499

Term of patent 3½ years

(Cl. D64—11)

FIG. 2.

FIG. 1.

The side opposite to that shown in Figure 2 is substantially similar thereto.

I claim:

The ornamental design for a printing tape register cabinet or similar article, substantially as shown and described.
